UNITED STATES PATENT OFFICE

FRED ALBERT DODELIN, OF GLEN RIDGE, NEW JERSEY, ASSIGNOR TO PYRENE MANUFACTURING COMPANY, OF NEWARK, NEW JERSEY, A CORPORATION OF DELAWARE

FIRE EXTINGUISHER

Application filed March 14, 1931. Serial No. 522,645.

This invention relates to fire extinguishers of the type shown, described and claimed in United States patent granted to Peter G. MacGregor, June 17, 1930.

An object of the present invention is to provide, in a fire extinguisher of the type above identified, certain improvements which relate particularly to the valve mechanism for simultaneously controlling the passage of compressed air or gas from the pressure chamber to the liquid chamber and the escape of the liquid from the latter when the liquid is subjected to such pressure.

A further object of the invention is to provide certain other improvements, relating particularly to the check-valve mechanism disposed in the air-line leading from the air pump to the pressure chamber and adapted to prevent back-flow of pressure, as when charging the pressure chamber by the pump.

Another object of the invention is to provide a novel and effective means for tying the heads of the extinguisher together in such a manner as to lend rigidity and strength to the fire extinguisher as a whole, and particularly to the one head common to the pressure chamber and the fluid chamber so that such common head may be so reinforced as to enable it to be made of relatively thin metal and yet withstand any and all pressures to which it may be subjected from within the extinguisher.

To the above and other ends, the invention consists in further improvements and arrangement of parts, all as will be more fully described, the novel features being pointed out in the claims.

In the drawings: Fig. 1 is a view partly in section and partly in elevation of a fire extinguisher embodying this invention; Fig. 2 is an enlarged central, vertical, sectional view taken on line 2—2 of Fig. 1 and in detail in the pressure and liquid valve mechanism thereof; Fig. 3 is an enlarged fragmental, central, sectional view of the check-valve assembly for the pump; Fig. 4 is a horizontal sectional view taken on line 4—4 of Fig. 2; Fig. 5 is a horizontal, sectional view taken on line 5—5 of Fig. 3; Fig. 6 is a vertical, sectional view taken on line 6—6 of Fig. 3; Fig. 7 is

a somewhat enlarged view in elevation of the upper end of the extinguisher of Fig. 1; Fig. 8 is a plan view of the extinguisher, as viewed from above in Fig. 7; Fig. 9 is an enlarged central, vertical, sectional view of a shut-off valve taken on line 9—9 of Fig. 8; Fig. 10 is a view, partly in elevation and partly in section, of a pressure and liquid valve mechanism, which is slightly modified with respect to the valve mechanism of Fig. 2; and Fig. 11 is a horizontal, sectional view taken on line 11—11 of Fig. 10.

The extinguisher, herein shown, includes a pair of heads 10 and 11, the former of which is preferably of cast metal and is provided with an upstanding flange 12, and the latter of which is preferably a sheet metal stamping, so formed as to provide a peripheral depending flange 14 and an upwardly extending pocket-like recess having a depending peripheral wall 15. Further, the extinguisher includes a liquid chamber 16, the lower end of the cylindrical wall of which is confined within the flange 12 and suitably connected to the head 10 to form therewith an air and liquid-tight joint, the upper end of such wall being confined within the flange 14 and suitably connected to the head 11 to form therewith an air and liquid-tight joint. Arranged within the liquid chamber 16 is a pressure chamber 17, the upper end of the cylindrical wall of which is confined within the depending wall 15 of the head 11 and is so connected thereto as to form with such head an air and liquid-tight joint, the lower end of the chamber 17 being spaced an appreciable distance from the bottom of the liquid chamber 16 and provided with an end wall 18.

Disposed within the pressure chamber 17, is a vertical pump cylinder 19, the upper end of which projects through the head 11 to which it is suitably connected and the lower end of which is embraced by and suitably secured to the upwardly extending flange 20 of a check valve housing 21, which constitutes one element of a pump check-valve assembly 13, hereinafter more particularly described. Within the pump cylinder 19, is arranged a reciprocating piston 22, adapted to be operated by a piston rod 24, guided in a cap mem-

55

60

100

ber 25, carried on the upper end of the pump cylinder. The outer end of the piston rod 24 carries a suitable handle 26, by which the pump may be readily operated. For the purpose of holding the piston rod in its depressed position, there is provided a bail 27, which is pivotally connected to the chamber 16 at substantially diametrically opposed points thereon. This bail is adapted to be moved onto an outwardly projecting boss 28, carried by a slidble collar 30, mounted on the piston rod above a fixed collar 31 carried by that rod, the collar 30 being normally urged upwardly by a coil spring 34, carried by the piston rod and disposed intermediate said collars. The pump, herein shown, is of the single-acting type, its piston 22 being such that it permits air to pass therearound on the upward stroke and such that it is caused to expand when acting on the air below the same during the compression stroke.

Leading from the lower end of the pump, is a pressure tube 35, which extends upwardly to the head 11 where it is connected to a valve block 36, the valve block being provided with air ducts 37 and 38 which may be placed in communication with each other, when desired, by a suitable valve hereinafter more particularly described. This valve block is connected to the head 11 in an inclined position, and is so located with respect to the pressure chamber 17 that communication between that chamber and the air pump may be established by way of the ports 37 and 38 and the pressure tube 35. For the purpose of establishing or severing communication between the pressure chamber and the air pump, there is provided a needle valve 40, the shaft portion of which is screw-threaded, as shown, and is adapted to engage similar screw-threads formed in the central bore of the valve block. The valve block may be provided with a suitable packing 41, disposed about the shaft portion of the valve, the packing being accessible from the exterior of the extinguisher upon removing its associated gland nut 42 carried by the valve block. To the outer end of the valve shaft, is connected a thumb wheel 44, by which the valve may be moved into and out of seating position to, respectively, sever and establish communication between the pressure chamber and the air pump, it being understood that the valve is to be open during such time as the pressure chamber is being charged by the pump and is to be at all other times maintained closed as a precaution against possible leakage of air from the pressure chamber by way of the pump check-valve assembly 13.

60 The housing 21 of the check-valve assembly 13, hereinbefore mentioned, is formed with a shoulder 43 which rests on the bottom wall 18 of the pressure chamber and includes a reduced shank portion 45 which projects through such wall and is pro-

vided with external screw-threads adapted to receive a clamp nut 47 between which and said shoulder the bottom wall of the pressure chamber may be clamped. Within the central screw-threaded bore 48 of the housing 21, is disposed a valve unit 50, which includes a screw-threaded head 51, having a peripheral groove 52 which serves as an air passage adapted to communicate with the air pump through a pair of vertical ducts 54 which extend through the transverse wall 53 of the housing intermediate the pump cylinder 19 and said valve unit. This annular air passage 52 communicates with a plurality of radial ducts 55, formed in the head 51; and these ducts, in turn, communicate with a central duct 56 leading into a valve chamber 57, within which is carried a ball valve 58, normally held in seating position by a spring-pressed plunger 60 of standard design. In the wall of the valve chamber 57, are formed a pair of openings 61, leading from that chamber to an air pocket 62, within which the valve chamber is located and from which leads the pressure pipe 35. From the check-valve assembly 13 thus far described, it will be apparent that as air is compressed in the pump cylinder by the piston 22 it is permitted to pass into the pressure chamber, assuming the valve 40 at the upper end of the pressure pipe 35 to be open, by way of the ducts 54, the annular passage 52, the radial ducts 55, the central duct 56, the valve chamber 57, the pair of openings 61, the air pocket 62, the pressure pipe 35, and the ports 37 and 38. The air in thus passing from the pump into the pressure chamber lifts the valve 58 from its seat, but as soon as the compression stroke is completed, or rather as soon as the force of compression is no longer sufficient to cause a passage of air from the pump to the pressure chamber, the valve 58 moves into seating position where it is firmly held by the spring-pressed plunger 60, thereby preventing back-flow of pressure from the pressure chamber to the pump, the ball remaining seated during the intake or suction stroke of the piston. Upon introducing the desired pressure into the pressure chamber 17, which may be determined by a suitable pressure gauge 64 carried by the head 11, the needle valve 40 is closed, thereby severing communication between the pressure pipe 35 and the pressure chamber 17, so as to guard against any possible leakage of pressure back into the pump by way of the check-valve 58. If desired, pressure may be introduced into the pressure chamber 17 through a suitable valve 65, secured to the head 11, the valve being of a well-known check type and provided with a cap 66 which may be screwed down onto the valve stem to insure against valve leakage, as will be readily understood.

Within the bore 48 of the valve assembly 130

housing 21, is placed a suitable packing material 67 which is held therein and in firm engagement with the screw-threaded head of the valve unit 50 by a pressure screw 68 which, like such valve unit 50, may be easily introduced into or removed from the valve assembly by way of an opening 70 formed in the head 10 directly beneath the housing 21 of such valve assembly. The packing 67, 5 as will be readily understood, serves to prevent any leakage of air past the valve unit 50 during the compression stroke of the pump. Inasmuch as the pump cylinder 19 is secured at one end to the head 11 and at its 10 other end to the housing 21 of the valve assembly 13, the two heads 10 and 11, may be effectively tied together with the aid of a lag screw 71, the shank of which projects through the opening 70 of the head 10 and 15 engages the screw-threads of the bore 48 of the housing 21. Such tying together of the heads 10 and 11 materially strengthens the extinguisher, as a whole, and particularly reinforces the head 11 against bilging upwardly 20 under the influence of pressure within the extinguisher. Due to the effective reinforcing thus afforded, the head 11 may be made from relatively thin sheet metal, such as brass, which readily lends itself to stamping 25 operations and thereby permits a considerable reduction in the cost of manufacture as compared with a cast metal head which would require certain relatively expensive metal working and finishing operations. 30 Moreover, by the present structure, the extinguisher head 11 and the bottom wall 18 of the pressure chamber are also tied together through the pump cylinder 19 and the housing 21 of the valve assembly 13; and, as 35 a result of this tie connection, the bottom wall 18 is reinforced against bilging downwardly under the influence of pressure within the pressure chamber 17, as will be readily understood, thus lending a further safety factor 40 to the extinguisher, as a whole, and at the same time permitting relatively thin sheet metal to be employed in the bottom wall of the pressure chamber with the result that such wall may be economically produced by 45 suitable stamping dies at a saving in cost of production as mentioned in connection with the head 11.

Upon the head 11, is mounted a valve mechanism 72, adapted to control the flow 50 of pressure from the pressure chamber 17 to the liquid chamber 16 and the escape of liquid from the liquid chamber through an outlet pipe 73, which is connected to the head 11 and to which may be attached a 55 nozzle tube, not shown, of the usual flexible type. The valve mechanism 72 includes a housing 74, having a flange portion 75, adapted to be suitably connected to the head 11 to form an air and liquid-tight union 60 therewith. The housing 74 includes a de-

pending portion 76, which projects through the head 11 into the liquid chamber 16 and contains adjacently disposed parallel valve chambers 77 and 78, which are screw-threaded and carry within their respective lower ends tubular screw-threaded plugs 80 and 81, provided at their respective inner ends with suitable valve seats, as shown. Within the chambers 77 and 78, are arranged pressure and liquid controlling valve heads 82 and 84, 70 respectively. The lower ends of these valve heads are pointed or shaped to conform to the respective seats of the plugs 80 and 81 and are provided at their upper ends with radial notches 85 and 86. The valve heads 82 and 84 are adapted to slide within tubular gland nuts 87 and 88, which serve to hold suitable packing in the upper ends of the chambers 77 and 78, the gland nuts being provided across their respective upper faces 75 with suitable slots, as shown, so as to permit them to be easily introduced into or removed from the housing 76 by the use of a suitable tool, such as a screw-driver, it being noted that access to the gland nuts, and hence 80 to the packing which these nuts normally hold in place about the valve heads 82 and 84, may be readily had from without the extinguisher upon removing from the valve assembly the valve heads and the valve-head actuating mechanism 90, hereinafter more particularly described.

The above-mentioned valve-head actuating mechanism 90 includes a rotatable shaft 91, carrying at its upper end a winged operating member 92 and provided at its lower end with screw-threads 94, the lead of which is opposite to that of the screw-threads 95 provided on the intermediate portion 96 of said shaft. Carried by the lower screw-threaded end of the shaft 91, is a nut or follower 97, having depending arms 98, spaced from each other and supporting a pivotally mounted transverse pin 100, to which is connected a yoke or connector member 101 disposed intermediate the arms 98 and having its ends projecting into the notches 85 and 86 of the valve heads 82 and 84. Carried by the intermediate portion 96 of the shaft 91 is an internally screw-threaded bushing 102, the upper end of which is provided with a flange, resting upon the upper end of a connector member 104, the lower end of which is screwed into the upper end of the housing 74 and the upper end of which carries a clamp nut 105, adapted to engage the flange of the internally screw-threaded bushing 102 and lock the same against rotation. As is obvious, the connector member 104 and the clamp nut 105 constitute and serve collectively in the capacity of a closure for the upper end of the housing 74.

From the above detailed description of the valve-head actuating mechanism 90, it will be apparent that by loosening the clamp 105

nut 105, the connector member 104 may be unscrewed from the housing 74, whereupon the valve-heads and valve-head actuating mechanism may be lifted, as a unit, clear of the housing. By removing the valve heads 82 and 84, together with the actuating mechanism therefor, access may be readily had to the gland nuts 87 and 88 to permit their being adjusted to compress the associated packing material or may be readily removed to permit the introduction of new packing material into the packing spaces provided in the housing at the upper ends of the valve heads.

Also from the above description of the valve-head actuating mechanism 90, it will be understood that as the shaft 91 is rotated, the nut or follower 97 is held against rotation by reason of the fact that the upper ends 20 of the valve heads 82 and 84, which are movable only vertically, project into the space offered between the arms 98 of such follower. If the shaft 91 is rotated in a counter-clockwise direction, regard being had to Fig. 8, such shaft, due to the lead of the screw-threads 95, will move upwardly with respect to the internally screw-threaded bushing 102, and the follower 97, due to the lead of the screw-threads 94, will move upwardly on 30 the shaft 91, with the result that the valve heads 82 and 84 are lifted from their respective valve seats a distance corresponding to the extent of longitudinal movement of the shaft 91, plus the extent of movement of the follower 97 upwardly on that shaft. Upon reverse rotation of the shaft 91, such shaft will move downwardly with respect to the bushing 102 and the follower 97 will move downwardly on the shaft 91, thus causing the 40 valve heads 82 and 84 to be moved downwardly a distance corresponding to the extent of the downward movement of the shaft 91 plus the extent of the downward movement of the follower 97 with respect to that shaft. It follows, therefore, that the valve heads may be moved, upon sufficient rotation of the shaft 91, into firm engagement with their respective seats, where they are effectively held by reason of the fact that the 50 pitch of the screw-threads 94 and 95 is such as to insure the shaft 91 against self-reversal due to such upward thrust on the valve heads 82 and 84 as may be inherent by reason of their having been forced into intimate engagement with their respective seats.

As to accurate seating of the simultaneously movable valve heads 82 and 84, it will be understood that such seating is insured by reason of the fact that the valve heads are capable of vertical movement with respect to each other to a substantial extent, inasmuch as they are operatively connected together by the pivotally supported yoke or connector member 101. Due to the fact that the valve heads are thus self-adjusting, wide variations

or tolerances, with respect to dimensions, may be permitted in the manufacture of the valve assembly, particularly in so far as such elements thereof as the valve heads, the valve seats and the yoke or connector member are concerned, with the result that the cost of production, with regard to the valve mechanism 72, may be kept at a minimum in the manufacture of extinguishers embodying this invention.

Suitably connected to the discharge chamber 17, is a pressure pipe 104', which extends upwardly and is connected to the screw plug 80 in alignment with the central passage thereof. This pressure pipe serves as is obvious when the valve head 82 is lifted from its seat, to establish communication between the pressure chamber 17 and the liquid chamber 16 by way of an air-port 105' formed in the wall of the housing 76 and communicating with the valve chamber 77, to which the pressure pipe is connected.

Connected to the screw plug 81, is a suitable pick-up tube 106' which extends downwardly in the liquid chamber substantially to the bottom thereof, the pick-up tube being provided at its lower end with a suitable strainer 107. This pick-up pipe is adapted to communicate with the valve chamber 78 when the valve head 84 is lifted from its seat, from which chamber leads a discharge pipe 108, partially encircling the upper end of the pressure chamber 17 and suitably connected, in turn, to the outlet pipe 73.

From the foregoing description, it will be understood that the extinguisher may be operated, assuming the liquid chamber 16 contains a suitable fire-extinguishing liquid and the pressure chamber 17 contains a quantity of gas or air under a substantial pressure, by so rotating the operating shaft 91 as to lift the valve heads 82 and 84 from their respective seats. Upon unseating the valve heads 82 and 84, communication is established between the pressure chamber 17 and the liquid chamber 16, thus permitting the escape of pressure from the former into the latter by way of the pressure tube 104', valve chamber 77 and air-port 105'. At the time the pressure chamber is opened to the liquid chamber, the latter is opened to the atmosphere by way of the pick-up tube 106', the valve chamber 78, the discharge pipe 108 and the outlet pipe 73 to which a suitable nozzle hose, not shown, may be connected. As pressure is supplied to the liquid chamber from the pressure chamber, liquid is forced out of the former by way of the pick-up tube 106', valve chamber 78, discharge tube 108, outlet pipe 73 and the nozzle tube previously mentioned. In order to close the valve heads 82 and 84, the hand wheel 91 is rotated in the proper direction to force such heads downwardly into intimate engagement with their respective seats.

Referring to Fig. 10, the valve assembly 72' shown therein is identical with the valve assembly 72 of Fig. 2, in so far as the elements of these two assemblies, that are identified by similar reference characteristics are concerned. The valve assembly of Fig. 10 differs, however, from that of Fig. 2 in that the valve head 82' is provided at its lower end with a cup-like recess 110, the bottom wall of which is adapted to engage a ball valve 111, whereby such valve may be urged into firm seating engagement with the valve seat of the screw plug 80 when the shaft 91 is so rotated as to move the valve heads 82' and 84 downwardly. Concerning the ball valve 111, it will be understood that as the valve head 82' is lifted, communication between the pressure chamber 17 and the liquid chamber 16 is established by reason of the fact that the ball valve is lifted from its seat under the influence of pressure within the pressure chamber 17. From the foregoing description of the valve assembly shown in Fig. 10, it will be understood that it may be readily employed in lieu of the valve assembly of Fig. 2, and that it possesses the several advantages hereinbefore enumerated with respect to that valve assembly.

It will be understood that various changes may be made in general and in detail with regard to the disclosure hereof without departing from the spirit of the invention or the scope of the following claims.

What is claimed is:

1. In a fire extinguisher of the type including pressure and liquid chambers from the former of which pressure is directed into the latter to expel the liquid therefrom, a valve mechanism for controlling the flow of pressure from the pressure chamber to the liquid chamber and for controlling the flow of liquid from the liquid chamber and comprising a housing having a pair of the valve chambers, valve-head actuating means comprising a rotatable shaft having a screw-threaded portion, a screw-threaded element carried by said screw-threaded portion and adapted to move longitudinally of said chambers upon rotation of said shaft and carrying a pair of arms spaced from each other, a pair of reciprocatory valve heads disposed within said chambers and having their corresponding ends disposed intermediate said arms whereby said screw-threaded element is retained against rotation at such time as said shaft is rotated, and a connector element disposed intermediate said arms and pivotally connected to the same and connected to said corresponding ends of said valve heads for relative movement with respect to the same.
2. In a fire extinguisher of the type including pressure and liquid chambers from the former of which pressure is directed into the latter to expel liquid therefrom, a valve

mechanism for controlling the flow of pressure from the pressure chamber to the liquid chamber and for controlling the flow of liquid from the liquid chamber and comprising a housing having a pair of the valve chambers, valve-head actuating means comprising a rotatable shaft having screw-thread connection with said housing and adapted to move longitudinally thereof upon being rotated, a valve-head operating member carried by said shaft for relative rotation with respect to such shaft and having a pair of arms spaced from each other, a pair of reciprocatory valve heads disposed within said chambers and having their corresponding ends disposed intermediate said arms whereby said valve-head operating member is retained against rotation at such time as said shaft is rotated, and a connector element disposed intermediate said arms and pivotally connected to the same and connected to said corresponding ends of said valve heads for relative movement with respect to the same.

3. In a fire extinguisher of the type including pressure and liquid chambers from the former of which pressure is directed into the latter to expel the liquid therefrom, a valve mechanism for controlling the flow of pressure from the pressure chamber to the liquid chamber and for controlling the flow of liquid from the liquid chamber and comprising a housing having a pair of the valve chambers, valve-head actuating means comprising a rotatable shaft having a pair of screw-threaded portions, the screw-threads of one portion being of an opposite lead to those of the other portion, means for connecting said shaft to said housing through said one of said screw-threaded portions whereby said shaft is caused to move longitudinally upon being rotated, a valve-head operating member carried by the other of said screw-threaded portions and adapted to move in a direction corresponding to the direction of longitudinal movement of said shaft and having a pair of arms spaced from each other, a pair of reciprocatory valve heads disposed within said chambers and having their corresponding ends disposed intermediate said arms whereby said valve-head operating member is retained against rotation at such time as said shaft is rotated, and a connector element pivotally connected to said valve-head operating member and connected to said corresponding ends of said valve heads for relative movement with respect to the same.

4. In a fire extinguisher of the type including pressure and liquid chambers from the former of which pressure is directed into the latter to expel liquid therefrom, a valve mechanism for controlling the flow of pressure from the pressure chamber to the liquid chamber and for controlling the flow of liquid from the liquid chamber and comprising a housing having a pair of the valve chambers, valve-head actuating means comprising a rotatable shaft having screw-thread connection with said housing and adapted to move longitudinally thereof upon being rotated, a valve-head operating member carried by said shaft for relative rotation with respect to such shaft and having a pair of arms spaced from each other, a pair of reciprocatory valve heads disposed within said chambers and having their corresponding ends disposed intermediate said arms whereby said valve-head operating member is retained against rotation at such time as said shaft is rotated, and a connector element disposed intermediate said arms and pivotally connected to the same and connected to said corresponding ends of said valve heads for relative movement with respect to the same.

- prising a housing having a pair of valve chambers, valve-head actuating means comprising a rotatable shaft having a screw-threaded portion, a removable closure for said housing, including a screw-threaded member connecting the screw-threaded portion of said shaft to said housing whereby said shaft is moved longitudinally of itself upon being rotated, a valve-head operating member carried by said shaft for relative rotation with respect to such shaft, a pair of reciprocatory valve heads disposed within said chambers, means for retaining said valve-head operating member against rotation at such time as said shaft is rotated, and a connector element pivotally connected to said valve-head operating member and connected to said valve heads for relative movement with respect to the same, said valve heads, said valve-head operating member and said shaft being removable as a unit from said housing upon removal of said closure.

5. In a fire extinguisher of the type including pressure and liquid chambers from the former of which pressure is directed into the latter to expel liquid therefrom, a valve mechanism for controlling the flow of pressure from the pressure chamber to the liquid chamber and for controlling the flow of liquid from the liquid chamber and comprising a housing having a pair of valve chambers, valve-head actuating means comprising a rotatable shaft having a screw-threaded portion, a removable closure for said housing, including a screw-threaded member connecting the screw-threaded portion of said shaft to said housing whereby said shaft is moved longitudinally of itself upon being rotated, a valve-head operating member carried by said shaft for relative rotation with respect to such shaft, a pair of reciprocatory valve heads disposed within said chambers, means for retaining said valve-head operating member against rotation at such time as said shaft is rotated, a connector element pivotally connected to said valve-head operating member and connected to said valve heads for relative movement with respect to the same, said valve heads, said valve-head operating member and said shaft being removable as a unit from said housing upon removal of said closure, packing material carried within said housing and disposed about said valve heads, and gland nuts screwed into said housing over said packing material and accessible through said housing upon removal of said closure.

6. A fire extinguisher comprising an upper head, a lower head having a lag screw opening, pressure and liquid chambers disposed intermediate said heads and from the former of which pressure is directed into the latter to expel liquid therefrom, a valve mechanism for controlling the flow of pressure from the pressure chamber to the liquid chamber and

for controlling the flow of liquid from the liquid chamber, a pump disposed within and extending longitudinally of said chambers and including a pump cylinder connected at one end to said upper head, a pump check-valve assembly connected to the other end of said pump cylinder and including a housing connected to a wall of said pressure chamber and projecting through the same into said liquid chamber and having a passage through which communication may be established between said pump and said pressure chamber, a check-valve insertable into and removable from said passage of said housing by way of said lag screw opening and a removable lag screw projecting through said lag screw opening into said housing and serving to tie said heads together through the medium of said pump cylinder and said housing.

7. A fire extinguisher comprising an upper head, a lower head having a lag screw opening, pressure and liquid chambers disposed intermediate said heads from the former of which pressure is directed into the latter to expel liquid therefrom, a valve mechanism for controlling the flow of pressure from the pressure chamber to the liquid chamber and for controlling the flow of liquid from the liquid chamber, a pump disposed within and extending longitudinally of said chambers and including a pump cylinder connected at one end to said upper head, a pump check-valve assembly connected to the other end of said pump cylinder and including a housing connected to a wall of said pressure chamber and projecting through said wall into said liquid chamber and having a passage through which communication may be established between said pump and said pressure chamber, a check valve insertable into and removable from said passage of said housing by way of said lag screw opening, means for anchoring said housing to said wall of said pressure chamber, including a shoulder provided on said housing and a nut carried by said housing between which and said shoulder said wall is clamped, a removable lag screw projecting through said lag screw opening into said housing and serving to tie said heads together through the medium of said pump cylinder and said housing and removable packing means carried within said housing intermediate said check-valve and said lag screw.

8. In a fire extinguisher of the type including pressure and liquid chambers from the former of which pressure is directed into the latter to expel liquid therefrom, a valve mechanism for controlling the flow of pressure from the pressure chamber to the liquid chamber and for controlling the flow of liquid from the liquid chamber and comprising a housing having a pair of valve chambers, a removable closure for said housing, valve-

head actuating means projecting through said closure and comprising a rotatable shaft having a screw-threaded portion, a screw-threaded element carried by said screw-threaded portion and adapted to move longitudinally of said chambers upon rotation of said shaft, means for retaining said screw-threaded element against rotation at such time as said shaft is rotated, a pair of reciprocatory valve heads disposed within said chambers, and a connector element pivotally connected to said screw-threaded element and connected to corresponding ends of said valve heads for relative movement with respect to the same, said valve heads, said screw-threaded element and said shaft being removable as a unit from said housing upon removal of said closure.

In testimony whereof, I have signed this specification.

FRED ALBERT DODELIN.
